C. H. ASBURY.
WHIFFLETREE.
APPLICATION FILED SEPT. 3, 1920

1,386,673.

Patented Aug. 9, 1921.

UNITED STATES PATENT OFFICE.

CHARLES H. ASBURY, OF POST FALLS, IDAHO.

WHIFFLETREE.

1,386,673.

Specification of Letters Patent. Patented Aug. 9, 1921.

Application filed September 3, 1920. Serial No. 407,828.

To all whom it may concern:

Be it known that I, CHARLES H. ASBURY, a citizen of the United States, residing at Post Falls, in the county of Kootenai and State of Idaho, have invented certain new and useful Improvements in Whiffletrees, of which the following is a specification.

This invention relates to means for attaching clevises to whiffletrees and has for its object to provide simple, inexpensive and efficient means whereby the wear upon the whiffletree will be minimized and accidental detachment or release of the clevis will be prevented. The invention is intended more particularly for use in connection with whiffletrees which are employed upon farms and are produced more or less roughly. These whiffletrees are provided with an opening near each end and an opening at the center through which clevis retaining pins or bolts are inserted, and heretofore the pins or bolts were very apt to work loose and ride up out of the said openings so that the clevises were accidentally released. Moreover, the strain applied to the whiffletrees was received directly by the wooden body of the same and the opening formed therethrough was enlarged so that the whiffletree was weakened and frequently split. All these objections are overcome by the use of my invention which is illustrated in the accompanying drawings and which will be hereinafter fully set forth.

In the drawings:

Figure 1 is a perspective view of a whiffletree equipped with my invention;

Fig. 2 is an enlarged perspective view showing the parts separated but approximately in their proper relative positions;

Fig. 3 is an enlarged transverse section of the whiffletree showing my improvement in position thereon.

The whiffletree 1 is of the usual dimensions and is equipped with an opening 2 near each end, and preferably nearer the rear side, and with a similar opening at the center and nearer the front side, the openings at the ends of the whiffletree being provided to permit the attachment of clevises for supporting swingletrees and the central opening being intended to permit the attachment of a clevis for connecting the whiffletree to a plow clevis or to a connecting ring or hook on a harrow or other farm implement. The central opening also provides for the attachment of the whiffletree to a draft pole

or tongue, but in such use the central clevis is not employed. In carrying out my invention, I employ a bracket or housing consisting of a vertically disposed web 3 having horizontal webs or flanges 4 extending from its upper and lower edges, the web 3 being adapted to fit closely against the front or rear side of the whiffletree and the flanges 4 being adapted to fit against the top and bottom of the whiffletree, as shown clearly in Fig. 3. At the side edges of the top flange 4, I provide the upstanding lugs or side plates 5 and through the flanges 4 I form openings 6 which are adapted to register with the openings 2 in the whiffletree. One of the side plates 5 is provided with a circular opening 7 therethrough and the other side plate 5 is provided with a horizontal slot 8 which is disposed at the same distance from the top edge of the plate as the opening 7 and with one end alined with the said opening. A retaining bolt or pin 9 is provided and the said pin or bolt is constructed with an elliptical head 10 which is so formed as to present a slot 11 therethrough. I also employ a key 12 which may be conveniently formed by bending the end portions of a stout wire at right angles to the main portion thereof, as shown at 13 and 14, the arms thus produced being of different lengths and the shorter arm being adapted to pass through the slots 11 and 8 as will be presently set forth. The clevis 15 is of any desired or well-known form and is provided at its ends with eyes 16 which are adapted to register with the openings 6 and 2 as is obvious.

In assembling the parts, the bracket or housing is fitted to the whiffletree, as shown in Figs. 1 and 3, so that the vertical web 3 will fit against the side of the whiffletree and the flanges 4 snugly engage the top and bottom thereof, it being understood that the brackets at the ends of the whiffletree are disposed so that their vertical webs will bear against the rear side thereof while the bracket at the center of the whiffletree bears against the front side of the same. The clevis is engaged over the whiffletree and the bracket so that its eyes will register with the openings through the bracket and the whiffletree and the pin or bolt 9 is then inserted through said eyes and said openings. In the drawings, I have shown the retaining member provided with the usual threaded extremity which engages the internal thread-

ed lower eye of the clevis. It is intended that the whiffletree and the bracket be of such vertical dimensions that the clevis will fit more or less snugly thereon but if the 5 distance between the arms of the clevis should be greater than the thickness of the bracket and the whiffletree, washers or liners may be inserted as is obvious. The elliptical head 10 of the retaining pin or bolt 9 is to be 10 disposed substantially parallel with the side plates 5 of the bracket after which the short arm 13 of the locking key is inserted through the opening 7 and the key turned so as to bring the major portion thereof into engagement with said opening and dispose the said arm in the plane of the slot 8, after which the key is pushed endwise bodily through the slot 11 in the head of the retaining pin or bolt and then through the slot 8. The key is 15 then turned so that its arms 13 and 14 will be disposed at right angles to the slot 8 and bear against the outer surfaces of the side plates 5, as shown in Fig. 1. Endwise movement of the key will be therefore prevented 20 and, of course, vertical movement of the member 9 cannot occur inasmuch as it is held down to the clevis by the key as will be readily understood on reference to Figs. 1 and 3 of the drawing.

25 It will be readily understood from the foregoing description, taken in connection with the accompanying drawings, that I have produced a very simple device by which the clevis will be securely held to the whiffletree and accidental release of the restraining pin or bolt will be effectually prevented. When draft is applied to the device the pull 30 will be received by the metal flanges 4 rather than by the wooden body of the whiffletree and the vertical web of the bracket will be drawn into close engagement with the whiffletree so that the latter will be effectually braced against breaking or splitting strain. As now ordinarily provided, the 35 threaded engagement of the retaining pin with the clevis is intended to hold the pin in place but the vibration of the swingletree carried by the clevis causes the pin to turn and work upward, eventually freeing itself 40 of the clevis and becoming loose. The threads then become battered and worn and will not hold but, in my device, the locking key prevents upward movement of the retaining pin so that the clevis is positively 45 secured in place. At the same time, the 50

clevis may be easily and quickly removed from or fitted to a whiffletree when necessary.

Having thus described the invention, what is claimed as new is:

1. The combination with a whiffletree having an opening therethrough, of a bracket having a vertical web to bear closely against one side of the whiffletree and horizontal flanges extending from the edges of said vertical web to snugly engage the top and bottom of the whiffletree and provided with openings to register with the opening through the whiffletree, side plates rising from the edges of the top flange, a retaining pin to be inserted through the said registering openings and retain a clevis in operative relation to the whiffletree, and means carried by said side plates and engaging the said retaining pin to prevent vertical movement thereof. 60

2. The combination with a whiffletree having an opening therethrough, of a bracket adapted to closely engage the top and bottom and one side of the whiffletree and having openings to register with the opening through the same, side plates rising from said bracket, one of said plates being provided with an opening therethrough and the other of said plates being provided with a horizontally extending slot, a clevis retaining pin adapted to be inserted through the openings in the bracket and the whiffletree and retain the clevis in operative relation to the whiffletree and provided with an elliptical head having an elongated opening therethrough, and a key comprising a straight body having laterally extending arms at its ends adapted to be inserted through the opening and the slot in the said side plates 80 and through the elongated opening in the head of the retaining pin with its arms engaging the outer surfaces of the said side plates at an angle to the slot therein. 90

3. The combination with a whiffletree, and a clevis, of upstanding supports on the whiffletree, a clevis-retaining pin inserted through the clevis and the whiffletree between said supports, and a key inserted through and carried by said supports and engaging the head of said pin to prevent the pin rising through the whiffletree and the clevis. 95

In testimony whereof I affix my signature.
CHARLES H. ASBURY. [L. s.]
